WELL PUMP OPERATING EQUIPMENT

Thomas Walker Murray, Texarkana, Tex., assignor to Texarkana Manufacturing Corporation, Texarkana, Ark., a corporation of Arkansas

Application April 9, 1940, Serial No. 328,781

6 Claims. (Cl. 74—44)

This invention relates to equipment for operating well pumps and more particularly to equipment for operating a pumping rod of a deep oil well pump.

Many oil wells, when completed, do not provide sufficient pressure to cause a natural flow of oil or well fluid to the surface of the earth. These wells, therefore, require use of a pump. In order that these well pumps may lift a substantial amount of oil or oil mixed with water, it is necessary to provide a relatively long stroke for the well pump plunger at the bottom of the well and a relatively long stroke for the sucker or pump rods. Deep wells require a longer stroke for the pumping rods than relatively shallow wells. This requirement for a longer stroke is due to the tendency of the pumping rods to stretch. It is found, for example, that where the pumping rods have a diameter between $\frac{5}{8}$ of an inch and $\frac{3}{4}$ of an inch, the stretch may be as much as 6 inches for each thousand feet of pumping rods. This stretch varies in accordance with the size of the pumping rods or tubing, the weight of the liquid being lifted, and the rate of operation of the pumping rods.

During recent years improved exploration facilities have developed many oil sands at a greater depth than the oil sands discovered at an earlier date.

It is, therefore, clear that the oil well art in its present stage of development requires a longer pumping stroke than it has in the past. There is also the need in this art for inexpensive pumping equipment which will provide efficient service with a relatively small power plant and with a minimum consumption of power.

Heretofore, oil well equipment has been relatively expensive, has required relatively large power plants, and has provided a relatively short working stroke for the pumping rods.

It is, therefore, an object of this invention to provide improved oil well equipment, which is particularly adapted to meet the needs of deep well pumping operations.

Another object is to provide improved oil well pumping equipment which will function efficiently with a relatively small and inexpensive power plant or engine and which may be used to provide a relatively long pumping rod stroke.

Another object is to provide oil well pumping equipment of improved construction and having a counterbalance for the combined weight of the well sucker rods and the liquid being lifted thereby, so that in each working stroke of the

sucker rods, the power consumption need only be sufficient to overcome frictional forces.

A still further object is to provide oil well pumping equipment which permits of its being readily modified to provide either a relatively long or short pumping stroke. A relatively long pumping stroke is particularly necessary for deep well pumps due to the stretch of their pumping rods and for oil wells producing large quantities of water or other fluid.

Another object is to provide oil well pumping equipment which permits the length of the pumping stroke to be readily increased without substantial increase in power or fuel consumption.

A further object is to provide oil well pumping equipment which will operate deep well pumps as efficiently and economically as shallow well pumps.

Another object is to provide oil well pumping equipment which will provide smooth, even operation of a well pump and cause the pumping rods to travel as fast on the upstroke as on the downstroke. The present invention avoids jerking action at the top and bottom limits of each pumping stroke. Such jerking action, which is characteristic of conventional equipment, is objectionable since it frequently causes breakage of sucker or pumping rods and may damage the well tubing. Accidents of this character are to be avoided as they may make it necessary to abandon a well.

Other objects and advantages will be clear from the following description, the appended claims, and the accompanying drawing which is a perspective view of an embodiment of this invention.

Referring now to the drawing, the illustrated equipment comprises a power plant 1, a clutch 2, a clutch pedal or operating lever 3, a transmission 4, and a gear shift lever 5, which are preferably connected for operation in the same manner as the corresponding parts of an ordinary automobile truck. The power plant 1, for example, may be a conventional Ford V-8 motor complete with radiator, or may be some other type of conventional automobile or truck motor. The clutch 2 is preferably a heavy duty clutch such as commonly used in a motor truck. The transmission 4 is preferably one adapted for heavy duty and may be a conventional Ford V-8 truck transmission.

The drive of the transmission 4 may be transmitted to a crank or power shaft 6 by means

including a conventional universal joint 7 interposed between short drive shafts 8 and 9, and suitable gearing in the gear box 10. The gearing in the gear box 10 may, for example, comprise reduction gearing. The power shaft 6 extends through the gear box 10 and from opposite sides thereof.

To the opposite ends of the crank or power shaft 6 are secured cranks or crank arms 13 and 14. These crank arms 13 and 14, for a purpose described hereinafter, extend from the shaft 6 in opposite directions. That is, the crank arms 13 and 14 rotate on the same or aligned axes, and the crank arm 13 is arranged at an angle of 180° relative to the crank arm 14. The cranks 13 and 14 will maintain this angular relation during operation so that as one crank arm is traveling downwardly the other crank arm will be traveling upwardly. If desired, crank wheels may be used in place of the crank arms 13 and 14. In this event, the crank wheels would be relatively arranged to provide the same drive as the crank arms 13 and 14.

A pitman or connecting rod 15 is connected by a crank pin 16 to the crank arm 14, and a pitman or connecting rod 17 is similarly connected by a crank pin 18 to the crank arm 13.

The illustrated equipment also includes a shaft 25 mounted for oscillation in stationary bearings 26 and 27. Each of these bearings 26 and 27 may be supported by a tripod 28.

A set of wheels 31, 32, 33, 34 and 35 are removably secured, as by means of keys, to the shaft 25. These wheels, as shown in the drawing, may be of similar size, that is their diameters may all be of the same dimension. The wheels 31 through 35 are preferably arranged in spaced relation relative to each other, and the wheels 34 and 35 are preferably mounted on the opposite ends of the shaft 25, which shaft ends extend beyond the bearings 26 and 27. The wheels 34 and 35 are illustrated as being spaced a substantial distance from the respective bearings 27 and 26 to avoid crowding of details in the drawing. In actual practice of this invention, it would be preferable to position the wheels 34 and 35 close to the bearings 27 and 26 respectively. The wheels 31 through 35 may each be in the form of a grooved pulley or sheave as illustrated in the drawing, in the form of a sprocket wheel, or in the form of a segment of a sheave or sprocket wheel.

Each of these wheels 31 through 35 is provided with a flexible member, these flexible members being numbered 41, 42, 43, 44 and 45 respectively. Each of these flexible means 41 through 45 may be in the form of a link chain, such as used for making sprocket chains, or in the form of a wire cable, depending on whether sprocket wheels or sheaves are used as the wheels 31 through 35. Each flexible member is trained over its respective wheel and suitably secured thereto. For example, a flexible member may have one end passed through an aperture in the rim of its respective wheel and may be provided with a clamp 47 to prevent the clamped end of the flexible member from being disengaged from the wheel rim. Each flexible member extends peripherally about its wheel from its clamped end to where it extends tangentially from the wheel rim. Each flexible member preferably is so connected to its respective wheel that it extends nearly all the way around the wheel periphery when the wheel is reversing its direction of movement and about to rotate in the direction for un-

winding the engaged portion of the flexible member.

As the shaft 25 oscillates, the wheels 31 through 35 oscillate therewith and, in effect, alternately wind up and unwind their respective flexible members (41 through 45).

The flexible members 42 and 43 serve as jack lines and are suitably secured to the pitmans 17 and 15 respectively. The jack lines 42 and 43 are trained over their wheels 32 and 33 in opposite directions, so that the jack line 42 projects downwardly from its wheel 32 at one side of the shaft 25, and the jack line 43 projects downwardly from its wheel 33 at the opposite side of the shaft 25.

With the crank arms 13 and 14 operating in the described and illustrated relation, and the flexible members 42 and 43 associated with their respective wheels 32 and 33 as illustrated and described, the shaft 6 during operation drives the shaft 25 in both directions of oscillation of the latter (shaft 25). The crank arm 13 on its down-stroke pulls on the jack lines 42 to rotate all the wheels 31 through 35 and the shaft 25 in one direction of rotation, (that is anti-clockwise looking at the drawing), while at the same time the crank arm 14 is traveling upwardly and the wheel 33, in effect, winds onto its periphery a longitudinal portion of the flexible means or jack line 43. When the crank arm 13 is on its upstroke, the crank arm 14 is traveling downwardly to operate its flexible means 43 and drive the wheels 31 through 35 and the shaft 25 in the clockwise direction, and the wheel 32, in effect, winds onto its periphery a longitudinal portion of the flexible means 42. It will thus be seen that the cranks 13 and 14 are effective to alternately pull or actuate the jack lines 42 and 43. As one crank arm is actuating its jack line, the other jack line 40 is being drawn in the reverse direction by the wheel to which it is secured.

The flexible means or pump line 41 is adapted to be clamped or otherwise secured to the upper end 50 of a string of sucker or pumping rods in well tubing 51. The pump operating equipment is preferably so positioned that the straight portion of the line 41 extends vertically from the pumping rod 50 to the periphery of the wheel 31.

The flexible means 44 and 45 are counter-balance lines and extend downwardly from the peripheries of their wheels 34 and 35 at the side of shaft 25 opposite to that side at which the pump line 41 extends downwardly. These flexible means 44 and 45 are each provided with a plurality of removable discs or weights 52 so as to counterbalance the total weight suspended by the pump line 41, including the weight of the sucker rods and the weight of the liquid to be lifted in each working stroke of the pump.

The length of the pumping stroke may be increased or decreased by replacing the wheel 31 with a wheel of different diameter. This substitution may be readily accomplished as the wheels 31 through 35 are each keyed to and detachable from the shaft 25. If it is not desirable to change the counterweights 52, the wheels 34 and 35 may be replaced by wheels having the same diameter as the wheel replacing the wheel 31. As an alternative to replacing the wheels 34 and 35, the counterbalance weights 52 may be changed in accordance with the gear ratio between the wheels 34 and 35 and the wheel replacing the wheel 31. In either case, it is preferable to counterbalance the weight of both the sucker rods and the liquid being lifted, so that the

pumping operation on the upstroke of the pumping rods requires a minimum amount of power. It will thus be clear that the pumping stroke may be increased without requiring an increase in power, the replacement of wheels 32 and 33 by 5 wheels of different diameter, or adjustment of the crank pins 16 and 18.

Conventional pumping equipment requires an increase of power when its pumping stroke is increased above 36 inches. The required increase in power is about 2 horsepower for each additional inch above a 36 inch stroke.

The length of the pumping stroke may also be changed by adjusting crank pins 16 and 18 toward or away from the crank shaft 6. To permit of this adjustment, each of the cranks 13 and 14 is provided with a plurality of spaced crank pin receiving apertures.

The illustrated equipment may be modified by shifting the crank pins 16 and 18 along their cranks 13 and 14 to apertures closer to the crank shaft 6, and by replacing the wheels 32 and 33 with wheels of smaller diameter. In this way, a shorter stroke of the crank pins 16 and 18 may be secured without changing the length of stroke 20 of the wheel 31.

In the appended claims, the term crank is used broadly to cover both crank arms and crank wheels; the expression cranks arranged at an angle of 180° relative to each other covers crank wheels with their respective crank pins on radial lines disposed at an angle of 180° relative to each other; the term wheel is used to cover a sprocket wheel, a sheave, and a section of a sprocket wheel or sheave; and the terms flexible means and cable are used to include such elements as a link chain or a wire cable serving the function and purpose of the flexible means illustrated in the accompanying drawing.

The above described equipment including the tripods 28 may be suitably mounted on skids 55, whereby the complete assembly may be readily slid along a derrick floor when being positioned for use or when being removed from a well. If desired, the skids 55 may be bolted or otherwise secured to the derrick floor during pumping operations.

The foregoing is illustrative, and it will be understood that this invention includes all modifications and embodiments covered by the appended claims.

I claim:

1. In equipment for operating the pumping rod of a well, the combination comprising: a shaft supported in elevated position for oscillatory movement about a horizontal axis; a set of at least three wheels operatively and detachably secured to said shaft for oscillation therewith; a flexible means, such as a cable, associated with each of said three wheels; each of said three flexible means having a portion secured to its respective wheel, another portion depending from said wheel, and an intermediate portion trained over said wheel; the flexible means associated with the intermediate one of said three wheels being a pumping line and having its depending portion adapted for attachment to a pumping rod in a well; the other two of said three flexible means having their depending portions adapted to support means for counterbalancing the weight of said pumping rod and its load in a working stroke thereof; and other means for driving said shaft in both directions of its oscillatory movement.

2. In equipment as recited in claim 1, wherein the set of wheels comprises five wheels, and the means for driving said shaft comprises means for alternately driving the fourth and fifth wheels to provide a drive for said shaft in both directions of its oscillatory movement.

3. In equipment for operating the pumping rod of a well, the combination comprising: a shaft supported in elevated position for oscillatory movement about a horizontal axis; a set of wheels operatively secured to said shaft for oscillation therewith; flexible means, such as a cable, associated with each of said wheels; each flexible means being attached to its respective wheel, being trained thereover, and having an end portion extending tangentially from its wheel, whereby each flexible means has a portion thereof wound on the respective wheel during movement thereof in one direction of oscillation and unwound during movement of the wheel in the other direction; two of said flexible means being jack lines and trained in opposite directions over their respective wheels; means for alternately operating said jack lines to drive said shaft in both directions of its oscillatory movement; a third of said flexible means extending vertically and downwardly from its respective wheel for operative connection with a well pumping rod, whereby the pumping rod is lifted during operation of said shaft in one direction of its oscillatory movement and is lowered by force of gravity during operation of said shaft in the other direction of its oscillatory movement; and means so supported by and associated with said shaft as to counterbalance at least the weight of said pumping rod during its reciprocatory movement.

4. Equipment as recited in claim 3, wherein the operating means for each of the jack lines comprises a crank and the two cranks are so relatively arranged and driven as to operate the jack lines in alternation.

5. In equipment for operating the pumping rod of a well, the combination comprising: a shaft supported for oscillatory movement about a horizontal axis; a set of wheels secured to said shaft for oscillation therewith; and flexible means, such as a cable, secured to each of said wheels; each of said flexible means being trained over and secured adjacent one end thereof to its respective wheel; two of said flexible means being jack lines and being trained over their respective wheels in opposite directions, whereby said jack lines are adapted to alternate in driving said shaft to oscillate the same, a third one of said flexible means being a pumping rod line and adapted for connection to a pumping rod to raise the same in one direction of oscillation of said shaft; two other of said flexible means carrying weight to counterbalance at least the weight of said pumping rod; the wheels provided with said weight carrying flexible means being arranged on said shaft at opposite sides of the wheel provided with said pumping rod line.

6. In equipment as recited in claim 5, a crank shaft, a set of two cranks carried by said crank shaft and extending therefrom in opposite directions, each crank being operatively connected to one of the jack lines, whereby said cranks during rotation of said crank shaft alternate in operating said oscillatory shaft to drive the same in both directions of its oscillatory movement.
